(57) **CLAIM**

We claim the ornamental design for a syringe drive device, as shown and described.

DESCRIPTION

FIG. 1 is a top perspective view of a syringe drive device of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a top perspective view thereof shown in a pulled back position;

FIG. 9 is a top perspective view thereof shown in an environmental use; and,

FIG. 10 is top perspective view thereof shown in an environmental use in the pulled back position.

The broken line showing of syringe drive device is included for the purpose of illustrating environment and forms no part of the claimed design.
